UNITED STATES PATENT OFFICE.

FRITZ ALDENDORFF, OF BERLIN-WILMERSDORF, GERMANY, ASSIGNOR TO PAUL KOLISCH, OF NEW YORK, N. Y.

ELECTROMECHANICAL TELEPHONE SYSTEM.

Application filed November 16, 1922. Serial No. 601,399.

To all whom it may concern:

Be it known that I, FRITZ ALDENDORFF, residing at 23 Brabanterstrasse, Berlin-Wilmersdorf, Germany, have invented certain new and useful Improvements in Electromechanical Telephone Systems, of which the following is a specification.

This invention relates to an electro-mechanical telephone system in which all the switches used have wipers that move in one plane only. An object of the invention is to provide a system in which efficient trunking arrangements can be obtained by comparatively simple means.

Another feature of the invention relates to novel metering arrangements. A further feature of the invention consists in providing wanted line connectors whose wipers are set onto any desired set of bank contacts by means of auxiliary switches which, in addition to designating the desired set of bank contacts, assist in performing other functions as for example restoring the switching apparatus to its normal position and applying a ringing current to the wanted subscriber's line.

The invention is illustrated in the drawing in which

Fig. 1 is a diagram of the general layout of the system,

Fig. 2 is a diagram representing the grouping of the various switches,

Fig. 3 illustrates how practically any desired trunking efficiency may be obtained with the aid of simple switches and

Figs. 4^a, 4^b, 5^a, 5^b and 6^a, 6^b, when placed side by side, represent a complete diagram of the circuits of the switches of Fig. 1.

The subscribers' talking connections are established through the voice current switches CC, GSI, TCI, GSII, TCII, and WC, Fig. 1, and during the operation of setting the said switches auxiliary switches, which are only used temporarily, are operated for the purpose of effecting rapid connections between a calling line or trunk and the next numerical switch ahead and for the additional purpose of guiding non-numerical switches onto a calling line or trunk. The auxiliary, temporarily-used switches are the switches CF, PT, DTI, ST, and DTII, TT, and IC, IH, IHII. The non-numerical switches are the switches CC, TCI and TCII, Fig. 1. The switches CC,

CF, TCI, DTI, TCII, DTII and WC will be assumed to have contact banks with one hundred sets of bank contacts each, while the numerical switches GSI and GSII have only ten sets of bank contacts each. The system shown in Fig. 1 will be assumed to have a capacity for ten thousand subscribers' lines divided into ten major groups of one thousand lines each and each major group will be assumed to have 10 minor groups of one hundred lines each.

The grouping of the switches and the trunking arrangements will be explained with the aid of Fig. 2. In this figure the rectangle above the double line 11 will be supposed to contain the switches belonging to the first group of one thousand lines, while the rectangle below the double line 11 contains the switches belonging to the second group of one thousand lines. The rectangles are divided into three columns by the vertical lines 12 and 13 and each rectangle I, II is divided into horizontal oblongs by horizontal lines, there being ten oblongs in each vertical column of each rectangle I, II. Pairs of switches CC, GSI are shown in the first five oblongs 1 to 5 of the first vertical column of the rectangle I, and pairs of switches TCI, GSII . . . TCII, WC are indicated in the first four and two oblongs respectively of the second and third vertical columns of the rectangle I. Pairs of switches CC, GSI . . . TCI, GSII . . . TCII, WC are also shown in some of the oblongs of the second rectangle II. Each of the said oblongs in an exchange according to the invention will be assumed to contain not only one pair but ten pairs of switches, one pair only being indicated in Fig. 2 for convenience of illustration. The switches CC, GSI in the first column are the ones that complete the first stage of a connection, i. e. the connection between a calling line and the wanted group of a thousand lines, the switches in the second vertical column complete the second stage of a connection in which the wanted group of one hundred lines is reached, and the switches, in the third column complete the third stage of the connection in which the calling party is connected to the wanted line. The group selectors GSI by which the wanted group of one thousand lines is selected have ten sets of bank contacts each

and the group selectors GSII are also ten-point switches. The first group selectors GSI have to enable calling subscribers to select any group of a thousand lines.

5 Hence the ten bank contact sets of each group selector GSI must lead to ten different thousand groups. The wiring between the first group selectors GSI is as follows: The first bank contact set, as k^1 of the 10 switch GSI, of each group selector in the oblong I in the first vertical column of the first thousand group I leads to a bank contact in each of the ten trunk connectors TCI in the first oblong 1 of the second vertical 15 column of the first thousand group I. Thus the ten first contact sets of the group selectors GSI in the first oblong of the first connecting stage are connected to ten trunks which are multiply connected to ten one 20 hundred-point finder switches or primary trunk connectors TCI in the first oblong 1 of the second connecting stage of the first thousand group I. The ten second contact sets of the first group selectors GSI in the 25 first oblong of the first connecting stage of the first thousand group I are connected to ten trunks which are multiply connected to primary trunk connectors TCI in the first oblong 1 of the second connecting stage of 30 the second thousand group II. The ten third contact sets of the ten first group selectors GSI of the first oblong 1 of the first connecting stage of the first thousand group I are connected to ten trunks which are multiply 35 connected to primary trunk connectors in the first oblong of the third thousand group (not shown) and so on.

The ten first bank contact sets of the first group selectors GSI in the first oblong 1 of the first connecting stage of the second thousand group II are connected to ten trunks which are multiply connected to the bank contacts of the ten primary trunk connectors TCI in the first oblong 1 of the second connecting stage of the first thousand group I. The ten second contact sets of the ten first group selectors GSI in the first oblong 1 of the first connecting stage of the second thousand group II are connected to ten 45 trunks which are multiply connected to the bank contacts of the ten primary trunk connectors TCI in the oblong 1 of the second connecting stage of the second thousand group II. The third bank contact sets of the ten first group selectors GSI in the first oblong 1 of the first connecting stage of the second thousand group II are connected to ten trunks which are multiply connected to the ten primary trunk connectors in the first oblong of the second connecting stage of the third thousand group (not shown) and so on.

55 The ten first bank contact sets of the first group selectors GSI in the second oblong 2 of the second connecting stage of the first thousand group are connected to ten trunks which are multiply connected to bank contacts of the ten secondary trunk connectors TCII in the first oblong 1 of the third connecting stage of the first thousand group I. The ten second bank contact sets of the ten second group selectors in the oblong 2 of the second connecting stage of the first thousand group I are connected to ten trunks which are multiply connected to bank

group I are connected to ten trunks which are multiply connected to the contact banks of the ten primary trunk connectors in the oblong 2 in the second connecting stage of the first thousand group I; the ten second bank contact sets of the first group selectors in the oblong 2 of the first connecting stage of the first thousand group I are connected to ten trunks which are multiply connected to the bank contacts of the primary trunk connectors in the second oblong 2 of the second connecting stage of the second thousand group II, and so on.

From the foregoing description it will be apparent that when a first group selector GSI connects the calling line through to a trunk leading to the particular thousand group selected the connection will be extended to a trunk in the second connecting stage by any idle one of ten different primary trunk connectors TCI. The connections with the third connecting stage are effected by means of the second group selectors GSII. The wiring between the second group selectors GSII and the secondary trunk connectors or finders TCII will now be explained: The ten first bank contact sets of the second group selectors GSII in the first oblong 1 of the second connecting stage of the first thousand group I are connected to ten trunks which are multiply connected to the contact banks of the ten one hundred-point secondary trunk connectors TCII of the first oblong 1 of the third connecting stage of the first thousand group I. The ten second bank contact sets of the second group selectors GSII in the first oblong 1 of the second connecting stage of the first thousand group I are connected to ten trunks which are multiply connected to the bank contacts of the ten secondary trunk connectors TCII in the second oblong 2 in the third connecting stage of the first thousand group I. The ten third bank contact sets of the ten second group selectors GSII in the first oblong 1 of the second connecting stage of the first thousand group are connected to ten trunks which are multiply connected to the bank contacts of the secondary trunk connectors in the third oblong 3 of the third connecting stage of the first thousand group, and so on.

The ten first bank contact sets of the second group selectors in the second oblong 2 of the second connecting stage of the first thousand group are connected to ten trunks which are multiply connected to bank contacts of the ten secondary trunk connectors TCII in the first oblong 1 of the third connecting stage of the first thousand group I. The ten second bank contact sets of the ten second group selectors in the oblong 2 of the second connecting stage of the first thousand group I are connected to ten trunks which are multiply connected to bank

contacts of the secondary trunk connectors in the second oblong 2 of the third connecting stage of the first thousand group I and so on.

5 The wiring between the second group selectors and the secondary trunk connectors in each of the other nine different thousand groups is similar.

10 It will thus be seen that when any second group selector has been set onto a trunk leading to any one of the ten different oblongs 1-10 or hundred groups of the third connecting stage of the particular thousand group in question the connection will be extended 15 to a wanted line connector WC by any idle one of ten different secondary trunk connectors TCII in the selected oblong or hundred group.

15 If all the switches in any set of ten primary 20 trunk connectors TCI should be engaged when a call is put through to this set the connection may be extended to the second connecting stage by an idle primary trunk connector in another oblong or set by arrangements made for this purpose in accordance with the invention. These arrangements are illustrated in Fig. 3.

25 At the left of this figure two groups of group selectors $G'S_i$ and G^2S_i are shown which correspond to group selectors in the two first oblongs 1 and 2 in the first connecting stage of the first thousand group I. The bank contacts of the group selectors $G'S_i$ and G^2S_i are connected to trunks which are multiplied in the banks of the trunk connectors TCI and TC^2I in the two first oblongs of the second connecting stage of the first thousand group I. D_{TI} and ST₁ are dialling trunk finders and secondary 30 trunk finders coordinated to the primary trunk connectors TC₁ in the first oblong 1 and DT₂, ST₂ are dialling trunk finders and secondary trunk finders respectively coordinated to the secondary trunk connectors in the second oblong 2 of the second connecting stage of the first thousand group I. The trunks leading from the banks of the group selectors, instead of being multiplied in the banks of the trunk connectors of only two oblongs will, in a 10000 line exchange, be multiplied in the banks of the connectors TC in ten oblongs. Ten trunks go from the group selectors GS_i of each oblong to each of the ten different sets of 35 trunk connectors TC₁ in the second connecting stage of the first thousand group I. Hence, the aggregate number of trunks emanating from all the group selectors GS_i in all of the oblongs 1, 2, 3 to 10 in the first connecting stage of the first 1000 group is 1000.

40 In order to enable the switches of any one of the number of other oblongs, say 2, 3, 4 and 5, to be used in case all the switches in any particular oblong, say 1 in the second

connecting stage of the first thousand, are all busy, one or two groups of overflow trunk connectors OTC may be provided in the second connecting stage of the first thousand. If two groups are provided each 70 group of overflow trunk connectors OTC may consist of switches whose banks comprise 500 bank contact sets to which one half of the thousand trunks emanating from all of the group selectors GS_i are multiply connected. Overflow dialling trunk finders DTF are associated with the overflow trunk connectors, these finders DTF being connected to the overflow trunks by overflow 75 trunk finders OTF, and the overflow trunks 80 being each associated with trunk finders CTF which are capable of connecting to any idle trunk in five different oblongs, say 1, 2, 3, 4, 5 in the second connecting stage of the first thousand group. 85

90 The operation of the overflow arrangement shown in Fig. 3 is as follows: Whenever a group selector, as $G'S_i$, is set onto a trunk leading to the trunk connectors of a certain oblong, as 1 of the second connecting stage of the first thousand group, and all the switches in this group are engaged at that moment, an overflow dialling trunk finder DTF is started and immediately connects the trunk selected by the group selector $G'S_i$ through to an overflow trunk by way of its overflow trunk finder OTF. The common trunk finders CTF, having all preselected a free, talking trunk, the dialling impulses from the calling subscriber will immediately flow through the switches DTF, OTF, CTF, to a free group selector, as for example GS_i^2 of the second oblong 2 in the second connecting stage 95 of the first thousand group. In the meantime an overflow trunk connector OTC is set onto the intermediate trunk that has been selected by a group selector GS_i^2 and the talking connection is then established 100 through an overflow connector OTC and a common trunk finder CTF. 105

110 The operations involved in establishing a connection between two subscribers will now be described in detail with the aid of Figs. 4^a, 4^b, 5^a, 5^b, 6^a, 6^b.

115 When a calling subscriber S raises his receiver a circuit is established through the subscriber's line and the line relay 100 of the calling subscriber is energized by a current which flows from the positive pole through 120 100, contact 101 of the cut-off relay 102, limb 103 of the subscriber's line, instrument S, limb 104 of the subscriber's line, contact 105 of relay 102, starting circuit wire 106, starting relay 107 to the negative pole of the battery. The starting relay 107 which is common to 50 subscribers of the one hundred subscribers of the group to which the calling subscriber S belongs is energized and closes 125 its contact 108 to complete a circuit for the 130

driving magnets 112 and 110 of the two quick-acting calling line finders CF¹ and CF associated with the temporarily used dialling trunks allotted to the group of the calling subscriber. The magnet 112 sets one set of wipers 113, 114, 115, 116, 117 of the calling line finder CF¹ in motion and the magnet 110 operates the wipers 118, 119, 120, 121, 122 of the calling line finder CF. The operated sets of wipers of the two finders CF and CF¹ start from different points or numbers in their respective contact banks so that one set of wipers will reach the calling line before the other, and will be supposed that the wipers 118, 119, 120, 121, 122 reach the calling line first. When the said wipers are thus set onto the contact set of the calling line a current flows from the negative pole through a contact 123 of a release relay 124, contact 125 of a relay 126, wire 127, windings of the hunting relay 128, hunting wiper 121, wire 129, contact 130 of the energized line relay 100, cut-off relay 102, contact 131 of the cut-off relay to the positive pole of the battery. The relays 128 and 102 are thus energized, the relay 128 opening the circuit of the operating magnet 110 at the contact 132 and the relay 102 cutting a resistance or metering relay 133 into the circuit by opening the contact 131. The metering relay 133 is, however, not energized at this time.

It will be mentioned here that as soon as the wipers of a calling line finder are moved out of their normal positions the operated magnet, as 110, is energized by a circuit that extends through a contact strip, as 134, and which is independent of the starting wire, as 135. It will also be mentioned that if a subscriber in the second group of 50 of the group of 100 subscribers had called a starting relay 107' would have been energized and would have closed a circuit through the operating magnets 109, 111 that move sets of wipers which travel over bank contacts of the second sub-group of 50 in the group of 100 subscribers.

The moment the cut-off relay 102 and the relay 128 are energized as described above the line relay 100 is disconnected from the line at the contact 101 and the circuit extending through the said relays 102, 128 then extends from the wire 129 through the contact 136 of the cut-off relay 102 instead of passing through the contact 130 which is opened on account of the deenergization of the line relay 100.

The relay 128, in addition to opening the contact 132, also opens the contact 137 and closes contact 138, 139, 140, 141, 142 and the calling line is then extended through the wires 143, 144, wipers 119, 120, contacts 141, 140, wires 145, 146 to the impulse relay 147, which is then energized by a current flowing from the positive pole through the right hand winding of the impulse relay 147

through 145, 141, 119, 143, 103, S, 104, 144, 120, 140, 146, left hand winding of 147 to the negative pole.

The impulse relay closes the contacts 148 and 149 and a circuit is thus closed which extends from the negative pole through 148 and the release relay 124, resistance 150 to the positive pole. The release relay opens its contacts 151, 123 and closes its contacts 152, 153 and 154, the contacts 152 and 154 being closed before the contact 123 is opened in order to avoid a temporarily de-energization of the relays 128 and 102 which, as described above, receive a current through the contact 123 until the contacts 154, 152 are closed when the current for the said relays will flow from the negative pole through 154, 152, and 127 to 128 and 102.

The closure of the contact 154 also results in the negative pole being connected to the wire 155 and to a bank contact 156 in the calling line identifier Ie. The closure of the contact 153 results in the energization of a slow acting relay 126 by a current flowing from the negative pole through 153, 126, 157 to the positive pole of the battery. The relay 126 on energizing closes a locking circuit for itself at the contact 158, and, at its contact 159, it closes an energizing circuit for the driving magnet 160 of the calling line identifier. The operating magnet 160 then moves the wipers 161, 162, 163 of the identifier Ie until the wiper 161 strikes a contact, as 156, connected with the negative pole, when a current flows through the stopping relay 164 to open the circuit of the operating magnet 160 at the contact 165 and to apply the positive and negative poles of the battery to the wipers 162, 163 through the relay contacts 166, 167.

The primary trunk finders PT, PT¹ associated with the calling line finders CF, CF¹ are each arranged so as to preselect different idle primary trunks as will be more fully described later. It will be assumed that the primary trunk finder PT has pre-selected a primary trunk so that when the impulse relay 147 was energized as described and closed its contact 149 a current flowed from the negative pole through 149, contact 169 of the relay 170, wiper 171, bank contact 172, wire 173, wire 174, contact 175 of the relay 176, wire 177, contact 178, impulse relay 179 to the positive pole. The impulse relay 179 will thus have been energized to close its contacts 180, 181, 182 and to open its contacts 183, 184. The release relay 185 is then energized by a current which flows from the negative pole through 181, 185, 186 to the positive pole, the said release relay closing a locking circuit for itself at the contact 187. A starting current or energizing current also flows from the negative pole through 187, 188 contact 189, operating magnet 190, interrupter 191 to the positive

pole of the battery and the wipers 192, 193, 194, 195 of the calling line connector or voice current calling line finder CC are then started and caused to hunt for the line of the 5 calling subscriber S who has appropriated the primary trunk PT for his call. The moment the line of this subscriber is reached by the wipers 192, 193, 194, 195, a current flows from the negative pole through 10 the contact 167 of the calling line identifier 1c, wiper 163, bank contact 196, wire 197, wiper 198, wire 199, wire 200, identifying relay 100', wiper 195, identifying wire 101', bank contact 102', wiper 118, contact 142, 15 wire 103', bank contact 104', wiper 162, contact 166 to the positive pole. The identifying relay 100' of the calling line connector CC is thus energized to open the circuit of the operating magnet 190 at the contact 189 20 and to prepare a circuit for the connecting relay 176 at the contact 105'. While the calling line connector CC, whose wipers will generally take much more time to reach the bank contacts of the calling line than the 25 wipers of the quick acting calling line finder CF, is operating in the manner described, the calling subscriber S can be sending in his dialling impulses for the purpose of selecting the wanted group of a thousand lines, say the second thousand group. To select the second thousand group the calling subscriber sets his dial so as to produce two interruptions of the current flowing through the impulse relay 147 in quick succession. 30 The impulse relay 147 is thus caused to open its contact 149 twice so as to give rise to two deenergizations of the impulse relay 179 in quick succession. The relay 179 is thus also deenergized twice to cause two closures of its contact 184, whereby two current impulses are caused to flow from the negative pole through 187, 184, 109', operating magnet 110' of the first group selector GSI to the positive pole. The wipers 111', 112', 113', 35 114', 115' are thus set onto the second bank contact set of the group selector which leads to an intermediate trunk *it*, that is connected to the banks of primary dialling trunk finders DT, DT' and to the banks of primary trunk connectors TCI located in the 40 wanted thousand group.

While the armatures of the impulse relay 179 are oscillating in response to the dialling impulses the changeover relay 116' is maintained energized by a current that flows from the negative pole through 187, 116', resistance 117' to the positive pole. But when the impulses cease the contact 182 is maintained closed to establish a continuous 45 short circuit around the change-over relay 116' and this relay is thus deenergized so that it closes its contacts 118', 119'. The closure of the contact 118' results in the closure of the circuit extending from the 50 negative pole through 118', contact 120' of the release relay 185, wire 121', connecting relay 176, contact 105' of the identifying relay 100', wiper 194, contact 136, cut-off relay 102, relay 133, positive pole. The relay 176 on energizing closes its contact 121' 55 to apply the negative pole through 122', 123', 124' to the resistance 150 so as to short circuit the release relay 124, which lets its armatures drop back and applies the negative pole to the left hand end of the relay 128 through 123, 125 and 128. The relay 124 is thus deenergized and opens its contacts 142, 141, 140, 139 and 138 while closing its contacts 137 and 132. The moment the contact 137 is closed the relay 126 is short-circuited by the negative pole being directly connected to the resistance 157 through 123, 125', 137, 140', 141' and 142'. A short interval will elapse before the slow-acting relay 126 lets its armature drop back to close 60 its contact 125 and to reconnect the negative pole to the wire 127 from which the said pole is disconnected when the armature contacts 152 and 151 are opened on the deenergization of the release relay 124. Thus 65 a short interval elapses during which the current from the negative pole through the lead 127 and the relays 128 and 102 is interrupted. Hence, if the calling subscriber S abandons a call before his line has been connected through to a group selector GSI by the calling line connector CC the two relays 128 and 102 will both be deenergized. But when the calling line has been connected through to a group selector GSI by a calling 70 line connector CC and the release relay 124 is deenergized on account of the energization of the relay 176 as described the relay 128 will be deenergized alone, the energization of the relay 102 being maintained by 75 a current that flows from the negative pole through 187, 188, contact 141', left hand winding of the connecting relay 176, contact 142' of 176, wiper 194, contact 136, relay 102 and the relay 133 to the positive 80 pole, the latter relay remaining deenergized.

When the relay 128 of the quick-acting finder CF is deenergized as described the set of wipers of the same that was set onto the calling line is restored to its normal position by the operating magnet 110 which is energized by impulses that flow from the positive pole through the interruptor 150', 110, contact 132, wiper 122, contact strip 134 to the negative pole. When the wipers 118, 119, 120, 121, 122 reach their normal position the circuit just described is opened on account of the brush 122 leaving the contact strip 134 and contacting with its insulated normal contact that is connected to the starting wire 135.

When the release relay 124 is deenergized the holding circuit (positive pole 164, 161, 156, 155, 154, negative pole) of the calling line identifier 1c is opened at the contact 154 130

and relay 164 is deenergized to close the contact 165 and thereby make the identifier Ie available for other calls.

The deenergization of the release relay 124 also results in the primary trunk finder PT being caused to set its wipers unto another primary trunk that is neither engaged for a conversation nor seized by another primary trunk finder PT^1 . This action of the primary trunk finder PT is started, when the release relay 124 is deenergized by a current which flows from the positive pole of the battery through contact 151, left hand winding of the relay 170 to the negative pole of the battery. The relay 170 thus energized then closes the circuit of the operating magnet 152' at the contact 151'. The operating magnet then receives impulses which flow from the positive pole through the interrupter 150², 151', 152' to the negative pole of the battery. The relay 170 is maintained energized as long as the wiper 153' of the primary trunk finder PT strikes bank contacts that are connected to the positive pole of the battery, and the contacts encountered by the wiper 153' and that belong to a trunk that has been seized by another trunk finder such as PT^1 will be connected to the positive pole through a back contact such as 154'. The bank contacts encountered by the brush 153' and belonging to engaged trunks will be connected to the positive pole by a contact 154' of the release relay 185 or through contacts 119', 155'.

In the intervals during which the wiper 153' travels from one bank contact to another the relay 170 is kept energized by impulses that flow from the positive pole through the interrupter 150², contacts 157', 156' left hand winding of the relay 170 to the negative pole of the battery. As soon as the wiper 153' lands on a bank contact that is not connected to the positive pole the current flowing through the left hand winding of the relay 170 is interrupted and relay 170 is deenergized whereby the operating magnet 152' is switched off and the positive pole is connected through the back contact 158' to the wiper 153' and to the corresponding bank contacts of the seized trunk so as to render this trunk inaccessible to other primary trunk finders.

Arrangements may be provided by which, in cases in which all of the trunks accessible to the primary trunk finders are engaged, these finders stop in a certain position until trunks become available.

When the release relay 116' was deenergized at the end of a series of dialling impulses as described above the positive pole of the battery was applied to the brush or wiper 114' through 154', 119', 159' and a starting relay 201, Fig. 5^a, was energized by current that flows through 114', 160',

starting relay 201 to the negative pole of the battery. The starting relay 201 closes its contact 202 and energizes operating magnets 212 and 210 of primary dialling trunk finders DT^1 . These dialling trunk finders are arranged similarly as the calling line finders CF , CF^1 and operate to connect the selected intermediate trunk it_1 through to a secondary trunk finder such as ST . As the dialling trunk finders DT , DT^1 were started by the starting relay 201 the dialling trunk finder DT will connect the intermediate trunk it_1 through by means of its relay 228. The calling line is now connected to the impulse relay 179 which by means of its contact 180 energizes the impulse relay 247 by a current that flows through 180, 162' of the relay 163' which is energized in a manner to be presently more fully described, contact 161', wiper 111', wire 243', 243, wiper 219, contact 241, winding of the impulse relay 247 to the positive pole.

The relay 163' was energized at the moment the intermediate trunk it_1 was reached by the wipers 218, 219, 220, 221 by a current from the negative pole of the battery through 223, 225, relay 228, wiper 221, wire 229, 229', wiper 113', relay 163', contact 119', contact 154' to the positive pole of the battery. The relay 163' thus energized encloses a locking circuit for itself through its contact 155' while increasing the resistance in the circuit of the relay 228 by opening the contact 231'.

The relays 226 and 224 of the secondary trunk finder ST are energized and the intermediate trunk identifier ItI is appropriated for the call in an analogous manner to that described in connection with the analogous relays 126, 124 and the calling line identifier Ie .

When the impulse relay 247 is energized it closes a circuit at its contact 249 for the impulse relay 279 and the calling subscriber, on sending in his dialling impulses for the selection of the wanted hundred group, causes the impulse relay 279 to operate and to give rise to energizations of the operating magnet 210' of the second group selector GSII. When the brushes 211', 212', 213', 214' land on the secondary intermediate trunk it^2 that leads to the switches TCI, DTI, DTII of the selected hundred group the starting relay such as 301 is energized by a current that flows from the negative pole of the battery through 301, 260', wiper 214', contact 259', contact 219', contact 254' to the positive pole of the battery and the starting relay 301 by closing its contact 302 energizes operating magnets 312, 310 of the secondary dialling trunk finders DTI, DTII, in an analogous manner to that described in connection with the relay 201 and the magnets 212, 210 in the

thousands selecting stage of the connection. A secondary dialling trunk finder such as DTI is then caused to set one set of its brushes, as 318, 319, 320, 321 onto the 5 secondary intermediate trunk it^2 and the impulse relay 347 is then energized by a current which flows from the positive pole through 347, 341, 319, 343, 343', 211', 261', 262', 280 to the negative pole of the battery, 10 the contacts 262' and 280 being closed by the relays 263' and 279 which are energized at this time, the relay 279 being energized by current flowing through the closed contact 249 of the relay 247 or through the 15 contact 278, wire 277, contact 277', wiper 293, wire 243', wiper 111', contact 161', 162', 180 to the minus pole of the battery, and the relay 263' being energized by current flowing from the positive pole through 20 255', 263', 213', 329', wiper 321, relay 328, contact 352, 354 to the negative pole.

The operations of the primary dialling trunk finders DT, the secondary trunk finders ST and the intermediate trunk identifier 25 It_1 are analogous to those of the calling line finders CF, primary trunk finders PT and the calling line identifier I_c so that they need not be more fully described here.

The operation of the primary trunk connector TCI is analogous to that of the calling line connector CC so that a detail description of the same is also unnecessary.

When the primary trunk connector TCI has connected the intermediate trunk it^1 35 through to the second group selector GSII the switches DT, ST, and It_1 are released and revert to common use.

The calling subscriber having now set the group selectors GSII, Fig. 4^b and GSII, 40 Fig. 5^b, onto the proper intermediate trunks by his two first sets or series of dialling impulses, will now send in a third series of impulses for the purpose of selecting the desired tens group in the selected 100 group 45 by means of the wanted line connector WC, Fig. 6^b. The subscribers tens dialling impulses directly affect the impulse relay 179, Fig. 4^b, and are translated by this relay to the relay 279, Fig. 5^b, which, in turn, translates the impulses to the impulse relay 347 50 associated with the tertiary trunk finder TT which will be assumed to have set its wipers onto the tertiary trunk that interconnects the secondary trunk connector TCII and the wanted line selector or connector WC.

When the impulse relay 347 oscillates the armatures it gives rise to breaks of the circuit that it previously closed through 349, 369, 371, 372, 373, 374, 375, 377, impulse relay 379 to the positive pole, and the impulse relay 379 is thus caused to oscillate its armatures so as to send current impulses from the negative pole of the battery through 378 of the release relay 385, (which was 60 previously energized by a current from the

negative pole through 381, 385, resistance 386 to the positive pole) 384, contact 400 of the change-over relay 316' (which is energized by current from the negative pole through 387, 382', 401) 402, operating magnet 403 of the tens designating switch T_d to the positive pole of the battery. The operating magnet 403 steps the wiper 404 onto a segment 405 and an arcuate wiper 406 onto bank contacts which are connected to 70 a normal contact 407 and to tens designating contacts 408, 409, 410 in the bank of the main switch of the connector WC. If only one tens impulse is sent in by the calling subscriber only one oscillation of the impulse relay 379 will take place and the magnet 403 will step the arcuate wiper 406 onto the first contact 411 of the tens designating switch T_d . The relay 431 will then be energized by a current which flows from the positive pole through 431, wiper 413, normal bank contact 407, bank contact 411, arcuate wiper 406 to the negative pole and the operating magnet 412 will receive an impulse which flows from the positive pole 80 through the interrupter 491, operating magnet 412, contact 434 of relay 430, contact 436 of relay 431 to the negative pole and will step the brushes or wipers 413, 414, 415, 416, 417 forward until they reach 90 a tens designating contact 408, 409, or 410 etc. which is not connected by the arcuate wiper 406 to the negative pole. In the case under consideration the arcuate wiper 406 is only stepped onto the first bank contact 100 411 so that the wipers 413, 414, 415, 416, 417 will stop as soon as the wiper 413 reaches the long bank contact or tens designating contact 408, when the relay 431 will be de-energized to open the circuit of the magnet 105 412 at 436.

If the subscriber had sent in two tens selecting impulses the arcuate wiper 406 would have been stepped round so as to apply the negative pole to the two bank contacts 411, 418 of the tens designating switch, and then the operating magnet 412 would have continued receiving impulses until the wiper 413 had been driven off the long contact 408 onto the second long contact 409, 110 which corresponds to the second group of ten bank contact sets in the wanted line connector WC. Each bank contact set comprises a horizontal row of four contacts corresponding to the wipers 414, 415, 416, 417. 115 Only three such bank contact sets are shown in each tens group instead of ten for convenience of illustration.

When the calling subscriber has sent in the tens selecting impulses a pause will issue during which the impulse relay 379 will keep its armatures steadily attracted.

It will be assumed that the secondary trunk connector TCII will, in the meantime, have found the secondary intermediate 120

trunk it^2 and that the dialling trunk finder DTI, the tertiary trunk finder TT and the secondary intermediate trunk identifier $ItII$, which operate in an analogous manner to 5 the corresponding switches in Figs. 5^a, 5^b, have reverted to common use, i. e. have been restored to normal. This being the case the impulse relay 379 of the wanted line connector WC will now be energized by a current 10 flowing from the positive pole of the battery through 379, 377, 377', 392, 343', 211', 261', 262' 280 to the negative pole of the battery.

When the calling subscriber now sends in 15 his units dialling impulses they will be received directly by the impulse relay 179 and this relay will translate them to the relay 279 which, in turn translates them to the relay 379. During the pause between the tens 20 and units impulses the change-over relay 316' was short-circuited on account of the negative pole being connected through 387, 382 to the resistance 386 so that the change-over relay allowed its armatures to drop 25 back and to close, at the contact 318^a, a circuit extending from the positive pole through 318^a, upper winding of relay 420, wire 421, arcuate wiper 406 to the negative pole. The relay 420 on energizing disconnects 30 the wire 423 from the operating magnet 403 of the tens designating switch and connects it through 422 to the operating magnet 424 of the units designating switch Ud . When the armatures of the impulse relay 379 oscillate in response to the units impulses the operating magnet 424 is then 35 energized by numerical impulses that flow from the negative pole through 387, 384, 400, 422, 424 to the positive pole and the magnet 424 then steps the wipers 425, 426, 427 around a corresponding number of 40 steps. Thus, if three units impulses are sent in by the subscriber the wiper 425 will be set onto the third bank contact 428 of the units designating switch Ud and the positive 45 pole of the battery will be applied to the contact 428 through 318^a, 430 and 425. It will be mentioned here that provision is 50 made to prevent the positive pole from being applied to a bank contact, as 428, of the units designating switch until the wiper 413 has been driven off the long contacts 408, 409 etc. that have been connected to the 55 negative pole by the arcuate wiper 406 of the tens designating switch Td . This provision is made for the purpose of preventing the stopping relay 430', that cooperates with the units designating switch Ud by 60 means of the wiper 414, from being operated unnecessarily in case units designating contacts, as 429, 429', 429'', of the main switch should have positive battery applied to them before the wipers 413, 414, 415, 416, 417 of the main switch WC have been driven 65 into the selected group of bank contacts.

The said provision consists in the relay 431 which is energized by a current from the minus pole of the battery through the arcuate wiper 406, long contacts of the main switch, wiper 413, 431 to the positive pole 70 and is thus caused to open its contact 430 and 432, the contact 432 and its associated interrupter 491' being provided for the purpose of assisting in restoring the tens designating switch Td to normal as will be hereinafter more fully described. 75

When the wipers 413, 414, 415, 416, 417 have been driven into the wanted group of sets of bank contacts by virtue of current impulses flowing from the positive pole 80 through 491, 412, 434, 436 to the negative pole, the relay 431 will be deenergized and the positive pole of the battery will be applied through 318^a, 430, 425 to the contact 428 and therefore to the units designating 85 contacts 429, 429', 429''. As the wiper 414 has travelled past the contacts 429'', 429', it will not strike a live bank contact until it reaches the contact 429 when a current will flow from the positive pole through 318^a, 430, 425, 428, 429, 414, relay 430' to the negative pole. The energization of the stopping relay 430' opens at contact 434, the circuit of the operating magnet 412 which, after the wiper 413 was driven off the live 90 contacts 408, 409, extended from the negative pole through wiper 427 of the units designating switch Ud , contact 435, 434, 412, 491 to the positive pole. When the wipers 413, 414, 415, 416, 417 are thus stopped on 95 the bank contact set belonging to the wanted line a test circuit is closed at 437 by the stopping relay 430'. This test circuit extends from the negative pole through 437, 100 test relay 438, test wiper 415, a test 105 wire similar to 439 and through the relay associated with the wanted subscriber's line. If the wanted line is busy a busy-tone circuit (not shown) which extends through contacts of the relays 430' and 438 110 and through an inductive winding on the relay 379 will be closed and apprise the calling subscriber of the fact that the wanted line is busy. The calling subscriber will then replace his receiver and the relays 179, 115 279 and 379 will be deenergized. These relays, by means of their contacts 183, 283, 383 will short circuit the release relays 185, 285 and 385 respectively. The relay 385 will then close restoring circuits at its contacts 440, 441, the one restoring circuit extending from the negative pole through the interrupter 492^a, contact 441, arcuate bank 120 405, wiper 404, operating magnet 403 of the tens designating switch to the positive pole and the other restoring circuit extending from the negative pole through 492^a, 440, wiper 426, arcuate bank contact 442 of the units designating switch, operating magnet 125 424 of this switch to the positive pole. The 130

operating magnet 424 drives the wipers 425, 426, 427 round until they reach their normal position. The operating magnet 403 drives the wipers 406, 404 around until the 5 wiper 404 leaves the arcuate bank contact 405. The tens designating switch T_d then stops for a while with the wiper 404 on the bank contact 443. The arcuate wiper 406 will now have connected the negative pole 10 to all the long contacts or group designating contacts 408, 409, 410 and hence current will flow from the negative pole through 406, long contacts with which the wiper 413 engages, relay 431 to the positive pole, and 15 this relay will be energized to close a circuit for the operating magnet 412 which extends from the negative pole through 436, 434, 412, 491 to the positive pole. When the wiper 413 with its associated wipers has 20 been driven into its normal position, that is the position in which the wiper 413 engages with the bank contact 407, the circuit of the relay 431, that extends from the negative pole through 406, 410 etc. 413, 431, is opened 25 so that the relay 431 opens the circuit of the operating magnet 412 at its contact 436 and closes a restoring circuit at 432 which extends from the negative pole through 491¹, 432, bank contact 443, wiper 404, operating 30 magnet 403 to the positive pole. The shape of the wiper 404 and of the contact 443 is such that this circuit through 403 is opened when the arcuate wiper 406 reaches the 35 normal position shown in which it is out of contact with the bank contact 411. The wanted line connector WC will then be fully 40 restored to its normal position, the locking circuits of the relays 420 and 430' having been opened at the contacts 387 and 446 respectively.

The restoration of the first group selector GSI and of the calling line connector CC takes place as follows: When the release relay 185 is deenergized it closes the circuit 45 that extends from the negative pole through interrupter 120², bank contact strip 120³, wiper 115', wire 115², contact 115³, operating magnet 110 to the positive pole. This circuit is maintained until the operating magnet 110 has driven the wiper 115' off the contact strip 120³ into its normal position. The selector GSI, whose relay 163' is deenergized by the rupture of its circuit at the contact 220' of the release relay 285 on the next 55 switch ahead as soon as the calling subscriber hangs up, will now be in its normal position.

The deenergization of the release relay 185 in the first group selector GSI also results in the circuit of the relay 176 and relay 102 being opened at the contact 120'. The calling line connector is then ready for a new connection without its wipers being stepped into any definite normal position.

The restoration of the second group selector GSII and of the primary trunk connector is similar to that of the switches GSI and CC, so that a detailed description of the operations involved in this restoration is unnecessary.

The secondary trunk connector TCII is restored by the circuit of its connecting relay 376 being opened at the contact 320' of the release relay 385.

It will now be assumed that the tested line is found idle when the test circuit including the test relay 438 is closed by the contact 437 of the stopping relay 430'. The test relay 438 will then be energized and at its contact 450 it will immediately close a preliminary ringing circuit which extends from the negative pole through wiper 427 of the units designating switch, contact 450, winding 452 of the ringing relay to the positive pole. The ringing generator 453 will then be immediately applied to the wanted line through the contacts 454, 455, and 456, 457. At the same time a restoring circuit for the units designating switch will be closed at the contact 458, this restoring circuit extending from the negative pole through the interrupter 491⁴, 458, wiper 426, arcuate bank contact 442, operating magnet 424 to the positive pole. The preliminary ringing current which is thus immediately sent out to the wanted line is interrupted when the units designating switch U_d reaches its normal position in which the preliminary ringing circuit (negative pole, 427, 450, 452, positive pole) is opened by 100 the wiper 427. Ringing current now continues to be applied intermittently by the relay 452 which is intermittently energized by current flowing from the negative pole through the bottom winding of 452, contact 461, contact 451, ringing current interrupter 460 to the positive pole.

When the wanted subscriber responds a current flows through the relay 462 over a circuit which extends from the positive pole to the left hand winding of 462, contact 463, contact 456, wiper 417, wanted subscriber's station, back to the wiper 416, contact 457, 464, right hand winding of 462 to the negative pole. The relay 462 then opens at its contact 461 the circuit of the ringing relay 452 and at its contact 465 it closes the circuit of the auxiliary release relay 466, this circuit extending from the positive pole through 465, 466 to the negative pole. The auxiliary release relay 466 closes a locking circuit for itself which extends through the left hand winding of 466, contact 467 and contact 387. The auxiliary release relay also closes at its contact 468 a metering circuit which extends from the negative pole through the retardation coil 469, 468, wire 469', contact 470, wiper 393, wire 343², wiper

212', contact 280³, winding of relay 281³ to the positive pole. The relay 281³ opens its contacts 278, 261', 280³, 282' after closing the contacts 283' and 284'. The impulse relay 279 is kept energized by a current flowing from the negative pole through 280, 262', 283', 279 to the positive pole. As soon as the contacts 284', 285' are closed the metering circuit is extended through 285', 277², 278', wiper 293, wire 293', wiper 112', contact 180³, winding 181³ to the positive pole. The relay 181³ is energized and at its contact 190' it closes a circuit which extends from the positive pole through battery 191', wire 192', coil 193' of the relay 176 to the negative pole. The coil 193' induces a momentary comparatively strong current in the winding 176 and thus in the circuit of the relays 102 and 133 and energizes the marginal relay 133 which closes the circuit of the conversation meter at the contact 198'. The marginal relay could also be energized by applying a comparatively strong battery directly to the wire 121'. The calling subscriber S will now be connected through the contacts of the relays 176, 181³, 281³, 376 to the retardation coil 469 and the impulse relay 379.

If the calling subscriber replaces his receiver first at the end of the conversation the current flowing through the impulse relay 379 and retardation coil 469 will be interrupted and the impulse relay will short circuit the release relay 385 at the contact 381. The tens designating switch TD and the main switch WC will then be restored as already described by restoring circuits extending through the contacts 441, 405, 404 and afterwards through the contacts 432, 443 and wiper 404. When the release relay 385 opens at contact 320' the relays 376 and 263' will be deenergized, the latter relay opening the circuit of the impulse relay 279 at the contact 262'. The impulse relay 279 will then short circuit the release relay 285 which will close the restoring circuit 220², 220², 215', 215³, 210' of the second group selector, while opening the circuit of the relay 276 and also of the relay 163' at the contact 220'. The relay 163' is thus deenergized and at its contact 162' it opens the circuit of the impulse relay 179 which then short circuits the release relay 185, this relay thereupon closing the restoring circuit of the first group selector GSI at 115³ and opening its contact 120' so as to deenergize the relays 176, 102, 133.

If the wanted subscriber replaces his receiver first at the end of the conversation the relay 462 will be deenergized and close the contact 490 so as to apply the positive pole through 490, 491 directly to the resistance 386. The release relay 385 is thus short circuited and initiates the disconnect

which proceeds in the manner already described. 65

I claim:

1. In an electro-mechanical telephone system, groups of subscribers' lines, primary talking trunks, secondary talking trunks, intermediate trunks between the primary and secondary trunks, a numeral selector associated with each said primary talking trunk, a non-numerical switch associated with each said secondary trunk, auxiliary trunks, auxiliary non-numerical switches adapted to connect an auxiliary trunk to any selected intermediate trunk and to any idle secondary trunk, and means for extending a call from a subscriber's line through a primary talking trunk, a numerical selector, and through an intermediate trunk and a secondary trunk connected to a said auxiliary trunk. 75 80

2. In an electro-mechanical telephone system, groups of subscribers' lines, primary talking trunks, secondary talking trunks, intermediate trunks between the primary and secondary trunks, a numeral selector associated with each said primary talking trunk, a non-numerical switch associated with each said secondary trunk, auxiliary trunks, auxiliary non-numerical switches adapted to connect an auxiliary trunk to any selected intermediate trunk and to any idle secondary trunk, means for extending a call from a subscriber's line through a primary talking trunk, a numerical selector, and through an intermediate trunk and a secondary trunk connected to a said auxiliary trunk, and means for disconnecting the said auxiliary trunk when a connection through the intermediate trunk and the secondary trunk is established. 95 100

3. In an electro-mechanical telephone system, group selectors, talking trunks, and finders each with a plurality of simultaneously hunting wipers for extending connections from the bank contacts of the group selectors to the said talking trunk. 105 110

4. In a telephone system, connectors each consisting of a rotary step-by-step switch with bank contacts connected to wanted lines and two auxiliary numerical switches adapted to steer the wipers of their associated switch onto a wanted line. 115

5. In a telephone system, connections each consisting of a rotary step-by-step switch with bank contacts connected to wanted lines and two auxiliary numerical switches adapted to steer the wipers of their associated switch onto a wanted line, and test circuits for testing a line onto which the wipers of the connector have been steered. 120

6. In a telephone system, connectors each consisting of a rotary step-by-step switch with bank contacts connected to wanted lines and two auxiliary numerical switches

permanently associated with each connector and adapted to steer the wipers of their associated switch onto a wanted line, test circuits for testing a line onto which the wipers 5 of the connector have been steered, and ringing means controlled by one of said auxiliary switches.

7. In a telephone system, connectors each consisting of a rotary step-by-step switch 10 with bank contacts connected to wanted lines and two auxiliary numerical switches adapted to steer its wipers onto a wanted line, and ringing means controlled by one of said auxiliary switches.

15 8. In a telephone system, connectors with bank contacts connected to wanted lines, two auxiliary numerical switches permanently associated with each connector and adapted to steer its wipers onto a wanted line, and connector restoring means controlled by a 20 said auxiliary switch.

9. In an electro-mechanical telephone system, groups of subscribers' lines, primary talking trunks, secondary talking trunks, 25 intermediate trunks between the primary and secondary trunks, a numeral selector associated with each said primary talking trunk, a non-numerical switch associated with each said secondary trunk, auxiliary 30 trunks, auxiliary non-numerical switches adapted to connect an auxiliary trunk to any selected intermediate trunk and to any idle secondary trunk, and means for extending a call from a subscriber's line through 35 a primary talking trunk, a numerical selector, and through an intermediate trunk and a secondary trunk connected to a said auxiliary trunk, the said auxiliary non-numerical switches being divided into switches 40 having contact banks with fewer bank con-

tacts than the banks of the non-numerical switches associated with the said secondary trunks.

10. In an electro-mechanical telephone system, groups of subscribers' lines, primary 45 talking trunks, secondary talking trunks, intermediate trunks between the primary and secondary trunks, a numeral selector associated with each said primary talking trunk, a non-numerical switch associated with each 50 said secondary trunk, auxiliary trunks, auxiliary non-numerical switches adapted to connect an auxiliary trunk to any selected intermediate trunk and to any idle secondary trunk, means for extending a call from 55 a subscriber's line through a primary talking trunk, a numerical selector, and through an intermediate trunk and a secondary trunk connected to a said auxiliary trunk, and overflow switches with bank contacts 60 connected to the banks of a plurality of groups of secondary non-numerical switches.

11. In a telephone system, connectors with bank contacts connected to wanted lines, two auxiliary numerical switches permanently 65 associated with each connector and adapted to steer its wipers onto a wanted line, and ringing means controlled by a wiper of one of said auxiliary switches.

12. In a telephone system, connectors with bank contacts connected to wanted lines, two auxiliary numerical switches permanently associated with each connector and adapted to steer its wipers onto a wanted line, and connector restoring means controlled by a wiper of one of said auxiliary 70 switches.

In testimony whereof I have affixed my signature.

FRITZ ALDENDORFF.

CERTIFICATE OF CORRECTION.

Patent No. 1,541,779.

Granted June 16, 1925, to

FRITZ ALDENDORFF.

It is hereby certified that the above numbered patent was erroneously issued to Paul Kolisch, of New York, N. Y., as assignee of the entire interest in said invention, whereas said Letters Patent should have been issued to the inventor, said Aldendorff, and Paul Kolisch, said Kolisch being assignee of one-quarter interest only in said invention, as shown by the records of assignments in this office; and that the said Letters Patent should be read with this correction therein that the same may conform to the record of the case in the Patent Office.

Signed and sealed this 24th day of May, A. D. 1927.

M. J. Moore,
Acting Commissioner of Patents.

Seal.
